(57) **CLAIM**

The ornamental design for a rotisserie basket, as shown and described.

DESCRIPTION

FIG. 1 is a perspective view of a rotisserie basket showing my new design, the portion in phantom lines in the figures forming no part of the claimed invention;

FIG. 2 is a front view thereof, the rear view, top view and bottom view being substantially similar thereto; and,

FIG. 3 is an end view thereof, the opposite end view being a mirror imager thereof.

1 Claim, 3 Drawing Sheets Fig. 2
